UNITED STATES PATENT OFFICE.

WALTER BRIGHT JEFFERSON, OF PHILADELPHIA, PENNSYLVANIA, ASSIGNOR OF ONE-HALF TO EDWARD JEFFERSON AND MORDECAI JEFFERSON, OF PHILADELPHIA, PENNSYLVANIA.

DRAWING-OFF ATTACHMENT FOR COMBING-MACHINES.

SPECIFICATION forming part of Letters Patent No. 730,021, dated June 2, 1903.

Application filed June 18, 1902. Serial No. 112,183. (No model.)

To all whom it may concern:

Be it known that I, WALTER BRIGHT JEFFERSON, a citizen of the United States, residing in the city and county of Philadelphia, State of Pennsylvania, have invented a new and useful Improvement in Drawing-Off Attachments for Combing-Machines for Wool, of which the following is a specification.

My invention relates to improvements in drawing-off attachments for combing-machines; and it consists of means whereby the endless aprons between which the long strands or "tops" pass are not subjected to the strain to which they are at present subjected, thereby prolonging the working qualities of said aprons and reducing to a minimum the necessity of replacing broken or worn-out aprons.

It also consists of novel details of construction, as will be hereinafter described.

Figure 1 represents a plan view of a portion of a combing-machine for wool having my drawing-off attachment herein described placed in position thereon. Fig. 2 represents a side elevation of certain of the parts seen in Fig. 1. Fig. 3 represents a partial side elevation and partial vertical section of certain of the parts seen in Fig. 2, the section being taken on line *x*-*x* in said Fig. 2. Fig. 4 represents a horizontal section of a portion of a grooved wheel employed in connection with my invention. Fig. 5 represents a side elevation of a portion of a grooved wheel employed and wires employed in connection therewith and illustrates the manner in which the tops or long strands of wool are retained on said wheel. Fig. 6 represents, on an enlarged scale, a plan view of certain detached portions of the device.

Similar letters of reference indicate corresponding parts in the figures.

Referring to the drawings, A designates a portion of a wool-combing machine, and the parts composing the same, except as herein-after claimed as new, belong to that type of machine known as the "Noble's combing-machine" and to which I have applied my improved drawing-off attachment.

B designates a ring which is provided with

the feed-boxes C, through which the slivers C' of wool are passed, said slivers being drawn from a ball or bobbin D', supported on a creel D, it being noted that only one bobbin D' is shown in the drawings, although in practice several of these are employed.

55

E designates a ring suitably supported on the frame of the machine, so as to turn thereon, it being noted that said ring is provided with pins F, which constitute a comb, and it is to be understood that in practice the pins F exist all the way around the ring E, although in the accompanying drawings these are shown only partly around said ring.

60

Located within the ring E are rings G, which are supported on steam-chests G' and adapted to turn thereon, it being noted that said rings G are provided with pins H' and that the rings G and pins H' constitute combs which operate in conjunction with the comb formed by the ring E and pins F, the object 70 of all of which will be hereinafter described.

65

H designates a wheel whose periphery is provided with serrations J' and grooves J, (similar to the grooves U, seen in Fig. 5,) it being noted that the wheel H has upon its upper face ratchet-teeth K, with which engages the inner end of a lever or breaker L, pivoted, as at M, to a suitable fixed point.

75

N designates wires, a portion of which are located in the grooves J, it being understood that one end of each of said wires is provided with a screw-threaded end adapted to receive a nut P, it being further understood that a spring R encircles each wire N and that said springs R are located between the nuts P and a fixed point Q and that the ends of the wires N opposite the screw-threaded ends thereof are secured to a fixed point S.

80

T designates a wheel, in the periphery of which are grooves U and serrations U', and the upper face of said wheel T is provided with ratchet-teeth V, with which engages one end of a lever or beater W, pivoted, as at W', to a fixed point.

90

It will be noted that a portion of the wire N occupies a position between the beater W and the comb formed by the ring E and pins F for a purpose hereinafter described.

95

S' designates a guide adapted to direct the ends of the wool which project within the circle E to the upper wire N, so that said ends may pass over said wire in order to be depressed by the beater W, as best seen in Figs. 2 and 3.

X designates a guide located adjacent the ring G and whose object is to direct the ends of the wool which project outside the ring G to the upper wire N, so as to be depressed by the beater L for a purpose hereinafter described.

A' designates a drawing-off roll to which motion may be imparted in any suitable manner, it being noted that said roll A' is journaled in a box C'', which is adapted to slide in a frame B' for a purpose hereinafter described. Bearing against said box C'' is a screw D', a portion of which is encircled by a spring E', which is located between one end F' of the frame B' and a cross-head K', secured to the screw D' and adapted to slide on the frame B', so as to normally retain the drawing-off roll A' close to the drawing-off roll J^X, adjacent thereto.

F' designates an endless apron which passes around the drawing-off rolls A' and G^X, it being noted that an endless apron H^X is located adjacent the apron F' and is passed around the drawing-off rolls J^X and operates in conjunction with the apron F' for a purpose hereinafter described.

It is to be understood that the ring G within the upper portion of the ring E (seen in Fig. 1) works in conjunction with drawing-off rolls, belts, wires, &c., similar to those described in connection with the ring G within the lower portion of the ring E.

The slivers fed from the boxes C are inserted between the pins F and H' by a dabbing-brush L^X.

The operation is as follows: The ends of the slivers C' are led from the balls D' to and through the feed-boxes C and are placed by hand over the pins F' and H' a short distance in advance of the dabbing-brush L^X, so that when said slivers C' reach a point beneath said brush the latter in its up-and-down movements will force the ends of the slivers between the pins F and H', so that said ends will be carried around by the rotation of the rings E and G, it being understood that the creels D move around with the ring E. The rings G do not move around with the ring E, but rotate on a stationary axis, thereby causing the ends of the wool inserted between the pins F and H' to separate, as indicated at a in Fig. 1. The ends of the wool which project outside the ring G are carried around by said ring and are caused to pass over the wires N and are depressed by the beater L, so as to cause said ends to hang in a vertical plane in order to be caught between the wires N and periphery of the wheel H in a manner similar to that seen in Fig. 5. The wheel H in rotating will cause the long strands of wool or tops to be withdrawn from the pins H' and

will convey said tops to the apron H^X, and when said tops are brought by the rotation of the wheel H to a point where they are no longer held between the wires N and the periphery of the wheel H said tops are conveyed by the apron H^X to the space between it and the apron F', where they unite with the tops that are withdrawn from the pins F by the wheel T, as seen in Fig. 1. The ends of the wool which project within the ring E are directed to the upper wire N by the guide S' and are bent down over the same by the beater W, as seen in Fig. 3. The ring E in rotating will cause the ends of the wool which are carried around thereby to become caught between the periphery of the wheel T and the wires N, and the wheel T in rotating withdraws the long strands of wool or tops from the pins F in the ring E, causing said tops to become separated from the wool in the ring E at a point indicated at b in Fig. 1. When the wheel T in rotating brings the tops carried thereby to a point where they are no longer held thereon by the wires N, said tops are drawn off the wheel T by the apron F' and are conveyed by the latter to the space between it and the apron H^X, where they unite with the tops delivered by the apron H^X and are carried off between said aprons F' and H^X to any desired point, as at c, in Fig. 1. The short wool or "noil" is carried around by the ring G, from which it is removed in the usual way, so as to leave the pins H' free to receive a subsequent supply of ends of wool, as hereinbefore described.

The manner of drawing the slivers through the feed-boxes C, so as to obtain the required length of fringe to be fed to the several combs, is accomplished in the usual way.

Motion is imparted to the aprons F' H^X, respectively, in any usual or preferred manner, as from one of the rolls G^X or J^X, and the roll A' may receive motion from the belt or apron F' thus driven.

The spring R yields when an extra thickness of tops are being drawn between the wires N and wheels H and T, thereby preventing injury to the wool. When an extra thickness of tops is being drawn off by the aprons F' and H^X, the spring E' yields and prevents injury to the wool.

By the employment of my invention I am enabled to increase the capacity of the machine and to obtain a much greater product than has heretofore been obtained.

Having thus described my invention, what I claim as new, and desire to secure by Letters Patent, is—

1. In a wool-combing machine, in combination with devices for feeding the wool, a rotatable comb-ring, a stationary guide adjacent thereto and adapted to receive the wool ends, a rotatable member contacting with said guide to draw the wool from said combing, and drawing-off devices adjacent said guide and rotatable member.

2. In a wool-combing machine, in combi-

nation with devices for feeding the wool, a stationary guide adjacent said comb-ring over which the ends of the wool are adapted to pass, a beater situated adjacent said guide to 5 depress said wool ends, a rotatable member contacting with said guide to draw the wool from said comb-ring, and drawing-off devices adjacent said guide and rotatable member.

3. In a wool-combing machine, in combination with devices for feeding the wool, a comb-ring, a stationary guide adjacent thereto over which the ends of the wool are adapted to pass, a rotatable member contacting with 10 said guide and adapted to draw the wool from said comb-ring, a beater adjacent said guide actuated by said rotatable member and drawing-off devices adjacent said guide.

4. In a wool-combing machine, devices for feeding the wool, a comb-ring, a stationary 15 guide adjacent thereto, a rotatable member contacting with said guide and adapted to draw wool from said comb-ring, a second rotatable member situated adjacent said feeding devices, a stationary guide adjacent said 20 second-mentioned rotatable member and drawing-off devices for removing the wool from the said rotatable members.

5. In a wool-combing machine, in combination with devices for feeding the wool, a 25 rotating member provided with peripheral

grooves, a stationary guide passing around and situated within the peripheral grooves of said rotatable member, and drawing-off devices for removing the wool from said guide and rotatable member.

35

6. In a wool-combing machine, in combination with devices for feeding the wool, a stationary guide adjacent thereto and adapted to remove the wool from the devices for feeding the same, drawing-off devices consisting of a plurality of traveling aprons situated adjacent said guide and adapted to engage between them the wool-tops removed by said guide.

40

7. In a wool-combing machine, in combination with devices for feeding the wool, a stationary guide adjacent thereto and adapted to remove the wool from the devices for feeding the same, drawing-off devices consisting of a plurality of traveling aprons situated adjacent said guide and adapted to engage between them the wool-tops removed by said guide, a portion of one of said aprons being movably supported so as to automatically adjust itself in accordance with the quantity 45 of wool being drawn off.
